UNITED STATES PATENT OFFICE.

DAVID F. GREENAWALT, OF YORK, PENNSYLVANIA.

FILE-CABINET.

No. 856,862.

Specification of Letters Patent.

Patented June 11, 1907.

Application filed June 7, 1906. Serial No. 320,627.

To all whom it may concern:

Be it known that I, DAVID F. GREENAWALT, a citizen of the United States, residing at York, in the county of York and State of Pennsylvania, have invented a new and useful File-Cabinet, of which the following is a specification.

This invention relates to filing cabinets, and has for its principal object to provide a cabinet in which papers may be filed away with but little difficulty and which may be made extensible, so that access may be had to all parts of the paper receiving compartments.

15 A further object of the invention is to provide a filing cabinet in which the box or casing is provided with a plurality of partitions, dividing it into a number of compartments, the partitions being connected to an opening 20 or spreading member by means of which the partitions may be moved away from each other, thus opening up the compartments and permitting the ready filing or withdrawal of the papers.

25 A still further object of the invention is to provide a device of this class in which the several partitions are maintained in parallel relation, so that the bottoms of the compartments will be of the same width as the top 30 or open ends, thus preventing the jamming or catching of the contents.

A still further object of the invention is to provide a cabinet having a plurality of vertically arranged movable partitions, and a 35 movable member forming a part of or carried by the door of the case and connected to all of said partitions, so that it may be moved for the purpose of spacing the partitions from each other and opening all of the 40 compartments.

A still further object of the invention is to provide a device of this class in which the cabinet or casing is provided with a hinged front arranged to swing in a vertical plane 45 and carrying a receptacle in the nature of a box or basket in which letters or other papers may be stored preliminary to filing.

A still further object of the invention is to provide a filing cabinet in which a number 50 of filing cases are mounted in a revoluble carrier and placed in a desk or other support, the carrier being freely movable to permit ready access to any of the cases.

A still further object of the invention is to

provide a filing cabinet including a revoluble 55 carrier and a plurality of filing cases, the carrier being arranged within a desk or similar structure having an opening through which the carrier is exposed, the tops of the several cases being arranged to lie flush with 60 the top of the desk.

A still further object of the invention is to provide a revoluble desk cabinet having a plurality of filing cases which may be adjusted to proper position, and moved or 65 lifted up through an opening in the top of the desk in convenient position for the filing or examination of papers.

With these and other objects in view, as will more fully hereinafter appear, the invention consists in certain novel features of construction and arrangement of parts, hereinafter fully described, illustrated in the accompanying drawings, and particularly 70 pointed out in the appended claims. 75

In the accompanying drawings:—Figure 1 is a perspective view of a portion of a desk provided with a filing cabinet constructed and arranged in accordance with the invention, parts being broken away in order to 80 more clearly illustrate the invention. Fig. 2 is a vertical section of the upper portion of the revoluble carrier, showing one of the filing cases in section. Fig. 3 is a similar view, showing the case moved to the top of the 85 desk and open. Fig. 4 is a transverse sectional view of a portion of the hinged front of the case, the section being on the line 4—4 of Fig. 3. Fig. 5 is a detail sectional view on an enlarged scale showing the manner in 90 which the partitions are connected together.

Similar numerals of reference are employed to indicate corresponding parts throughout the several figures of the drawings.

In carrying out the invention, the desk 10 95 or other suitable supporting casing is provided with an opening 11 in the top or cover member, and within said desk or case are arranged bearings for the reception of the pin-tles or shaft 15 of a revoluble carrier 16. 100 The carrier may be formed of wood or of metal, and its periphery is arranged to extend slightly through the opening 11. This revoluble carrier or drum is provided with a plurality of radially arranged peripheral 105 compartments 16, which are arranged to receive the several filing cases or cabinets 17. Each case or cabinet comprises a bottom

member 18, a back 19, ends 20, a hinged front 21, and a hinged top or cover 22. The top or cover 22 is arranged to lie flush with the top of the desk when in the closed position illustrated in Fig. 2, and is provided with a sunken handle 24 which may be grasped when the case is to be raised above the top of the desk for examination of its contents or the filing of papers. The several filing cases, of which there may be any number, are so arranged that any one of them may be adjusted to a position opposite the opening 11, and when in this position, the top or cover will form a part of the desk top.

15 The hinged front 21 is arranged to fold down to a horizontal position in alignment with the bottom 18 of the case, and this hinged front is provided with a longitudinal groove 26 for the reception of a number of headed studs 27 that are carried by a slideable plate 28, said plate having flanges 29 on three of its sides, so that when moved to the position shown in Fig. 3, it may be used as a box or basket into which letters or other 20 papers may be thrown preliminary to filing.

25 Arranged within the case 17 are vertically disposed partitions 30 which may be formed of cardboard, wood, sheet metal or any other material, and these are preferably connected together by folding or bellows side and bottom members 31, which will permit the movement of the partitions toward and from each other, the partitions, however, remaining at all times in parallel relation, so that 30 the papers cannot become jammed at the bottom of the compartments.

35 The bottoms of the partitions are connected at the center to a flexible tape or band 32, the front end of which is connected to the plate 28, and when this plate is pulled out to the position shown in Fig. 3, the tape will be stretched, and the partitions will be opened to the fullest extent, so that ready access 40 may be had to the several filing compartments.

45 Normally the flanges 29 of the slideable plate extend over the front edges and the inner portion of the top of the case and serve as dust excluding members. When it is desired to gain access to any one of the filing cases, the drum may be readily rotated by the fingers until the top of the desired case appears at the opening 11. The case may then be raised to a point above the top of the 50 table, and the front folded down, so that the case will remain in position on top of the desk. The plate 28 is then drawn out, and by this single movement all of the partitions 55 are spread and the compartments opened to the fullest extent.

60 It will be observed that when in open position, the case has a bottom of very large area which will insure its standing in upright po-

sition while the papers are being filed away or examined.

65 I claim:—

1. In a file cabinet, a casing having a hinged front movable to open position in alignment with the bottom of the case, a series of partitions arranged within the case, a flexible member connecting said partitions, and a receiving box connected to said flexible member and slideable over the front to thereby draw the partitions outward.

2. In a filing cabinet, a case having a hinged front, a plurality of partitions arranged within the case, a flexible connecting means between said partitions, and a slideable member carried by the front and connected to the flexible member to permit spacing of said partitions.

3. The combination in a filing cabinet, of a case having a hinged front, a plate slideably mounted on said front, a plurality of partitions within the casing, and means connecting the slideable plate to the partitions.

4. In a filing cabinet, the combination with a case having a hinged front member, a slideable plate arranged on the inner face of said front member and provided with a marginal flange, partitions arranged within the case, and means for connecting said partitions to the slideable plate.

5. In a filing cabinet, the combination with a case, having a hinged front member, of a flanged plate slideably mounted on the inner face of the front and serving when in closed position as a dust guard, and when in open position as a receiving box or basket, a plurality of partitions within the case, flexible bottom and side members connecting the partitions and forming compartments, and a flexible strip connected to all of said partitions, and also connected to said flanged plate.

6. In filing cabinets, the combination with a supporting case having an opening at the top, of a revolute carrier arranged within the case and having its periphery projecting slightly through the opening, a plurality of filing cases mounted on the carrier and adjustable into alignment with said opening, and means for sustaining the filing cases in elevated position, and at the same time preventing rotation of the carrier.

7. In filing cabinets, the combination with a casing having an opening at the top, of a revolute carrier arranged within the casing and having a portion of its periphery projecting into the opening, and a plurality of file cases supported by the carrier and having flat covers movable into alignment with the upper surface of the casing top.

8. In filing cabinets, the combination with a casing having an opening in its top, of a revolute carrier arranged within the casing

and provided with radial pockets, and a plurality of filing casings arranged within the pockets and movable into alinement with the opening, said filing casings having movable tops and fronts, the top members being movable into alinement with the top of the casing.

5 In testimony that I claim the foregoing as

my own, I have hereto affixed my signature in the presence of two witnesses.

DAVID F. GREENAWALT.
